UNITED STATES PATENT OFFICE.

MICHAEL M. SWEETMAN, OF KANSAS CITY, MISSOURI.

METHOD AND APPARATUS FOR REMOVING LIQUID AND SALT DEPOSITS FROM GAS WELLS.

Application filed July 18, 1921. Serial No. 485,434.

To all whom it may concern:

Be it known that I, MICHAEL M. SWEETMAN, a citizen of the United States, residing at Kansas City, in the county of Jackson and State of Missouri, have invented certain new and useful Improvements in Methods and Apparatus for Removing Liquid and Salt Deposits from Gas Wells, of which the following is a specification.

10 This invention pertains to an improved method and apparatus for removing liquid and salt deposits from gas wells.

The main object of the invention is to provide means which may be attached to a well 15 casing whereby fluid under pressure may be caused to force the water upwardly and out of the well, provision also being made for the introduction of water into the well in case the well should become closed from salt 20 deposits therein, this with a view of dissolving the salt and thereafter forcing the salt water from the well.

One embodiment of the apparatus by 25 which the operation may be effected, is shown in the annexed drawings, wherein a well tubing is illustrated in section, together with the pertinent apparatus employed for withdrawing the gas, and likewise the necessary apparatus for introducing the solvent 30 for the salt or other incrustations into the well, the showing being more or less dia-grammatic.

In said figure, 1 denotes the well tube or 35 casing and 2 a head secured thereto, from which extends an off-take pipe 3, having a shut-off valve 4 located therein. Said pipe 3 extends into a drip tank 5, of any approved form, having a float controlled valve 6 therein. An off-take 7 leads from said 40 tank to a main 8, or any other point to which the gas, in the ordinary operation of the well, is to be delivered. Mounted within the pipe or casing 1, and spaced away from the interior wall thereof, is a hollow member or 45 conduit 9, preferably formed of a series of connected sections having transverse dia-phragms 10 therein which divide the tubu-lar member 9 thereby formed into a series of chambers 11. Pipes 12 are mounted in 50 the cross partitions 10, the lower end of one pipe extending well down into the chamber below and terminating short of the adjacent partition, while the upper end extends to a point above the partition and past the lower 55 end of the pipe which is carried by the par-

tition next above. There is thus formed a series of pockets or chambers which are in-terconnecting through the pipes 12, the low-ermost pipe opening into the bottom of the well. The uppermost pipe 11 extends 60 through a plug or block 13 secured in the upper end of the tubular member 9 and has connected thereto a lateral branch pipe 14 provided with a stop valve 15, said pipe 14 being in communication with the off-take 65 pipe 3 to the outer side of the valve 4. A second valve 16 is provided upon the fitting extending from the uppermost pipe 12. 17 denotes a tank or reservoir, preferably port-able, adapted to contain any fluid, as air or 70 gas, under a high degree of compression, and is in communication with the interior of the well tube 1 through a pipe 18, pro-vided with valves 19 and 20. The pipe 18, intermediate the valves, is provided with a 75 suitable connection 21 which opens into a tank 22 provided with a filler plug 23. Said tank 22 is provided with an off-take or con-nection 24 which extends through the head 2 and is thus brought in communication with 80 the well tubing or casing 1. A valve 25 is provided in the line 24.

In operation, assuming that it be merely desired to remove water from a gas well, valves 4 and 15 will be closed, valve 16 will 85 be opened and valve 25 closed, that is, as-suming tank 22 is connected in. The opera-tor then attaches the tank 17 to the line 18 and opens the valves 19 and 20, thereby per-mitting the gas under pressure to pass into 90 the well casing 1 and force the water in the well downwardly and then upwardly through pipes 12, the water successively passing from one chamber 11 to the other, and finally finding its way through the up-95 permost pipe 12 and out of valve 16. Valve 16 is then closed, valve 15 fully opened, and valve 4 opened to such an extent that a dif-ferential pressure is held between the well tubing and the tubular member 9 sufficient 100 to lift a column of water which can be deter-mined by the amount of water the well is making. By closing valve 15 and opening valve 16 the operator can immediately de-termine whether or not the apparatus is 105 working properly.

To utilize tank 22, valves 19, 20 and 25 are closed and the tank filled with water or other solvent. When the tank is filled and closed, valve 25 is opened wide and valve 110

20 opened enough to allow the liquid to flow into the well at the required speed. The liquid will dissolve the salt and the elevator, that is, the tubular member 9, will carry 5 the salt solution out of the well and deposit it in the drip tank 5.

It will, of course, be understood that the tanks 17 and 22 are additions to the usual well equipment and are used at different 10 times.

They are preferably portable so they may be employed on different wells at such times as there happens to be salt present, or the water elevator is to be started; or when blowing the water out of a well that is 15 equipped with a plain pipe inserted inside of the tubing and commonly known to those skilled in the art as a siphon and the gas pressure on the well is not sufficient to lift the liquid. The length of the elevator 20 tubing 9 is determined by the rock pressure of the well and the pressure carried in the transportation line.

For the purpose of further explanation, let us assume the well to be 2,000 feet deep, 25 and that one would put in 100 sections to make up the tubular member 9, each section approximately 20 feet long. Now assume that there is enough water coming into the well to put a four inch body or plug of 30 water into the bottom tube 12 every few seconds. By the time the first body of water gets out of the top of the well, there will be a four inch plug or body of water in each of the 100 tubes, which would be the same as a 400 inch column of water, and require a little less than 15 lbs. pressure to throw the water out of the top, while if the tube were continuous, the water would keep 35 on accumulating in the well and continuously run back on the inner surface of the pipe, and finally one would get a column of water which would overbalance the pressure, and the well would then shut off. With the present device the water is trapped at each diaphragm or cross partition 10, and from that 40 point would be ejected to the next succeeding chamber, thus preventing it from reflowing. In actual practice the water does not accumulate quite so fast as to make four 45 inches in the pipe every few seconds, and, in fact, not even fast enough to make one inch. The gas travels at a high rate of 50

speed and sprays the water into each chamber. While the water is gradually accumulating around the bottom of the tube in each 55 chamber the gas is picking it up and carrying it on upwards and spraying it into the next succeeding chamber and so on. With the use of the present device the well is automatically kept clean and produces its 60 full capacity at all times.

What is claimed is,—

1. In combination with a well tubing; a water conduit located within the same; a portable tank adapted to contain a fluid under a high degree of pressure; means for placing the tank in communication with the tubing; means to control the flow of water from the conduit; and means for controlling the flow of gas from the well. 70

2. In combination with a well tubing; a water conduit located therein, said conduit having a series of chambers in its length, and a tube extending from one chamber to the next; a valved pipe extending from the uppermost tube to the gas take-off; a valve controlling said take-off; a portable tank containing a liquid under pressure; and means for connecting said tank to the upper portion of the well casing. 80

3. That method of removing water from flowing gas wells which consists in inserting a conduit for the water within the well casing, said conduit comprising a series of interconnected chambers which serve to trap the water and thereafter admitting fluid or gas to the well casing under pressure to force the water to flow upwardly through the conduit and to eject the same from one chamber to the next above and finally out 90 of the well. 85

4. That method of removing water from flowing gas wells, which consists in inserting a conduit for the water within the well casing, said conduit embodying a series of interconnecting chambers in the form of traps, and thereafter admitting fluid or gas to the well casing under sufficient pressure to cause the water to flow upwardly through the traps in succession. 100

In testimony whereof I have signed my name to this specification.

MICHAEL M. SWEETMAN.
